UNITED STATES PATENT OFFICE.

ISIDOR KITSEE, OF PHILADELPHIA, PENNSYLVANIA.

PRINTING-TELEGRAPH.

No. 922,781.

Specification of Letters Patent.

Patented May 25, 1909.

Application filed August 25, 1908. Serial No. 450,127.

To all whom it may concern:

Be it known that I, ISIDOR KITSEE, a citizen of the United States, residing in the city of Philadelphia, county of Philadelphia, and 5 State of Pennsylvania, have invented a new and useful Printing-Telegraph, of which the following is a specification.

My invention relates to printing telegraphy and more particularly to printing telegraphy 10 when practiced over a long land line, a submarine or other cable, or in any relation where the impulses arriving at a receiving station are feeble.

My invention resides in a printing telegraph in which synchronism between the transmitting and receiving apparatus is not necessary, the receiving apparatus being controlled by a line or cable relay responsive to feebly received impulses, such relay controlling master step by step mechanisms each of 15 which is capable of controlling a plurality of printing circuits, each master also controlling a plurality of associate step by step mechanisms, each of which controls a plurality of 20 printing circuits.

The transmitting apparatus may be a simple hand-operated key, a tape transmitter, or any other suitable type of transmitter which will impress upon the line or cable electrical 25 impulses of relatively short duration and which succeed each other at relatively short and preferably equal intervals, such impulses being all positive, all negative, or part positive and part negative. The initial positive 30 impulse or impulses impressed upon the line or cable control one master step by step mechanism, while the initial negative line impulse or impulses control another master step by step mechanism, and these master 35 mechanisms each control a plurality of associate step by step mechanisms each of which controls one or more printing circuits.

For an illustration of one of the forms my invention may take, reference is to be had to 40 the accompanying drawing, which is a dia-grammatic view of the circuits and apparatus of the receiving printing apparatus.

L represents a telegraphic line or cable in which at a receiving station is connected the 45 winding of a polarized relay R whose tongue or armature is normally at rest midway between the two contacts 1 and 2, under the influence of the spring 3. At the transmitting station there are impressed upon the line or 50 cable L a plurality of relatively short im- pulses, either positive or negative, which

succeed each other at relatively short intervals. If, at the transmitting station a short positive impulse be impressed upon the line, the relay tongue t will momentarily 55 engage the contact 1 and then return to normal position. This short contact, however, suffices to allow current to flow from the battery 4 through the winding of the sluggish relay magnet 5 through the tongue t, 60 contact 1, conductor 6, thence through the winding of the electro-magnet 7, conductor 8 to the contact b of the master step by step mechanism B, thence through the brush 9, which is mechanically and electrically connected with the notched metallic wheel 10, thence through the brush 11, which is always in electrical communication with the wheel 10, thence by conductor 12 to the other pole of the battery 4. In consequence, the 65 quickly acting electro-magnet 7 is energized and attracts its armature carried by the pivoted lever 13 to which is pivoted a second lever 14 which engages the teeth upon the notched plate 15 of the master step by step 70 mechanism A. In consequence, the notched wheel 15 is stepped around in a clockwise direction, an angular distance corresponding with the angular width of a tooth, and is there locked, the brush 16, carried by wheel 15, being then moved off of contact a on to contact a¹. If, now, no other line impulse, either positive or negative, is transmitted the brush 16 remains upon contact a¹ and the printing magnet 17 is momentarily energized 75 because the sluggish magnet 5 has attracted its armature lever 18 to break circuit at contact 19, thus allowing full current from battery 20 to flow through conductor 21, conductor 22, winding of the magnet 17, contact a¹, brush 16, wheel 15, conductor 23, thence through the three pairs of contacts 80 24, 25; 26, 27; and 28, 29, associated respectively with the notched wheels 30, 31 and 32 of the controlled associate step by 85 step mechanism A³, A² and A¹. When these wheels are in normal position these pairs of contacts are in engagement with each other, as shown, thus rendering the conductor 23 continuous. The current passes on then 90 through conductor 33, conductor 34, thence through conductor 35 to the other pole of the battery 20. The printing magnet 17 being 95 thus energized prints a character in the well known manner.

Between the conductor 35 and one pole of the battery 20 is connected the winding 36 of

a sluggish magnet which is also energized when the printing magnet 17 is energized, but operates somewhat more slowly and eventually causes the armature lever or tongue 37 to engage contact 38 thus closing a circuit through the battery 39, conductor 40 and all of the magnets 41, 42, 43, 44 in series with each other thence through conductor 45, and all the magnets 46, 47, 48 and 49, all 10 in series with each other, thence through conductor 50 to the tongue or armature 37, thus causing all these magnets to be simultaneously energized. Each, accordingly, attracts its dog 51, but since all the step by 15 step mechanisms, except A, are in normal position, there is no effect except in the case of magnet 49 which, when it attracts its dog 51, releases the notched wheel 15 of the master mechanism A, which then returns to 20 normal position under the influence of the spring 52, the pin 53, carried by wheel 15, coming against the brush 54, which is always in contact with the wheel 15, thus bringing the wheel 15 to a rest at normal position. 25 Similarly, if only a short negative impulse be impressed upon the line or cable L at the transmitter, the tongue t of the relay R momentarily engages contact 2, whereupon current flows from the battery 4, through 30 the winding of the magnet 5, tongue t, contact 2, conductor 55, winding of electromagnet 56, conductor 57 through contact a of master A, brush 16, wheel 15, brush 54, conductor 58 to the other pole of the battery 4, thus energizing the quickly acting magnet 35 4 and causing it to step the wheel 32 around until the brush 76, carried thereby and in electrical communication therewith, engages contact 77, whereupon printing magnet 78 is energized by current from battery 20, the magnet 5 being so sluggish that the circuit at 40 19 is not interrupted because of the extremely short contact between t and contact 1 due to the positive impulse immediately followed by a negative impulse. Then immediately after the printing magnet 78 has 45 been energized and a character printed the sluggish magnet 36 has again responded to energize all of the releasing magnets, whereupon wheel 15 of master A and wheel 32 of the mechanism A' are restored to normal by 50 their respective springs. The stepping of the wheel 32, however, has allowed contact 29 to separate from contact 28 thus breaking the circuit including the conductors 23 and 32. Upon restoration to normal, however, 55 the pin, carried by the wheel 32, has again closed circuit at 28 and 29.

It is to be noted also that the movement of the brush 16, of master A, to contact a' has prevented current from passing through 60 the magnet 56, of the master B, because the circuit is open at contact a of master A. Similarly, if two positive line impulses are succeeded by a negative line impulse, the brush 16, of master A, is quickly stepped 65 around into engagement with contact a' and then the contact between t and 2 allows current to pass from battery 4 through conductor 55, through the winding of the magnet 79 of the step mechanism A², thence through 70 conductor 80' to contact a' of master A, brush 16, wheel 15, brush 54, conductor 58, to the other pole of the battery 4, thus causing the brush 80, carried by and in electrical 75 communication with the wheel 31 of the step mechanism A', to engage contact 81 thus allowing current to pass through the printing magnet 82. Or, if three positive line impulses are succeeded by a negative line impulse, the master A steps the brush 16 80

immediately succeeded by a negative impulse. The relay tongue t first engages contact 1 but for an instant only, inasmuch as the succeeding negative impulse quickly causes the tongue t to move across into engagement with contact 2 and then assumes its normal position midway between the contacts. The engagement with contact 1 causes, as heretofore described, the magnet 7 to step the wheel 15 around so that the brush 16 engages the contact a' of the master A. The contact between t and 2 results in current flowing from the battery 4 through the winding of the magnet 5, tongue t, contact 2, conductor 55, winding of the electromagnet 74, conductor 75, contact a' of master A, brush 16, wheel 15, brush 54, conductor 58 to the other pole of the battery 4, thus energizing the quickly acting magnet 74 and causing it to step the wheel 32 around 85 until the brush 76, carried thereby and in electrical communication therewith, engages contact 77, whereupon printing magnet 78 is energized by current from battery 20, the magnet 5 being so sluggish that the circuit at 90 19 is not interrupted because of the extremely short contact between t and contact 1 due to the positive impulse immediately followed by a negative impulse. Then immediately after the printing magnet 78 has 95 been energized and a character printed the sluggish magnet 36 has again responded to energize all of the releasing magnets, whereupon wheel 15 of master A and wheel 32 of the mechanism A' are restored to normal by 100 their respective springs. The stepping of the wheel 32, however, has allowed contact 29 to separate from contact 28 thus breaking the circuit including the conductors 23 and 32. Upon restoration to normal, however, 105 the pin, carried by the wheel 32, has again closed circuit at 28 and 29.

It is to be noted also that the movement of the brush 16, of master A, to contact a' has prevented current from passing through 110 the magnet 56, of the master B, because the circuit is open at contact a of master A. Similarly, if two positive line impulses are succeeded by a negative line impulse, the brush 16, of master A, is quickly stepped 115 around into engagement with contact a' and then the contact between t and 2 allows current to pass from battery 4 through conductor 55, through the winding of the magnet 79 of the step mechanism A², thence through 120 conductor 80' to contact a' of master A, brush 16, wheel 15, brush 54, conductor 58, to the other pole of the battery 4, thus causing the brush 80, carried by and in electrical 125 communication with the wheel 31 of the step mechanism A', to engage contact 81 thus allowing current to pass through the printing magnet 82. Or, if three positive line impulses are succeeded by a negative line impulse, the master A steps the brush 16 130

around into engagement with contact a^3 , in which case the succeeding negative impulse causes current to pass through the winding of the operating magnet 83 of the step mechanism A^3 until its brush 84 engages contact 85 allowing current to pass through the winding of the printing magnet 86. Or, if, in any of the last three cases described, more than one negative impulse succeed the initial positive 10 impulse or impulses the brush 76, or the brush 80, or the brush 84 is stepped around a corresponding number of spaces to engage a corresponding contact and thereby close the circuit through a corresponding printing 15 magnet.

If the received impulses be one negative followed by one or more positive impulses the master B controls the step mechanism B^1 having actuating magnet 130, wheel 87 and brush 88 to step around a number of spaces corresponding with the number of received positive impulses to engage one of the five associated contacts to control one or the other of the five associated printing magnets in the 20 group 89, 90, 91, 92 or 93. Or, if two initial negative impulses be followed by one or more positive impulses, then the step mechanism B^2 having actuating magnet 129, wheel 94 and brush 95 is stepped around to close the 25 circuit of one of the printing magnets 96, 97, 98, 99 or 100, depending upon the number of positive impulses. And, similarly, if three initial negative impulses be succeeded by one or more positive impulses, 30 then the master B controls the step mechanism B^3 , having actuating magnet 128, wheel 101 and brush 102, to step that brush around a number of spaces corresponding with a 35 number of positive impulses to close the circuit of one of the printing magnets 103, 104, 40 105, 106, 107 or 108. If either more than three positive or more than three negative initial impulses are received the associated step mechanisms A^1 , A^2 and A^3 , B^1 , B^2 and B^3 45 are not actuated but, in the case of more than three positive impulses, either contact a^4 or contact a^5 , of master A, is engaged by brush 16, and either one or the other of printing magnets 109 110 is energized; or in the case 50 of more than three negative impulses the brush b^4 or b^5 of master B, engages either contact b^4 or b^5 to energize either printing magnet 111 or printing magnet 112.

In the case of step mechanism A^3 , if three 55 initial positive impulses are succeeded by more than one negative impulse, the brush 84 is stepped around a number of spaces corresponding with the number of negative impulses, so that one of the printing magnets 60 113, 114 or 115 is energized; and, similarly, in the case of step mechanism A^2 , if the two initial positive impulses be succeeded by more than one negative impulse, the brush 80 is stepped around a number of spaces 65 corresponding with the number of negative impulses, so that one or the other of the printing magnets 116, 117, 118, or 119 is energized, and in the case of step mechanism A^1 , if the one initial positive impulse be succeeded by more than one negative impulse the 70 brush 76 is stepped around a number of spaces corresponding with the number of negative impulses, so that one or the other of the printing magnets 120, 121, 122, or 123 is energized. Thus, it is seen that by the 75 two master step mechanisms, one responsive to positive impulses and the other to negative impulses, and with three associated step mechanisms controlled by each master, each associate mechanism controlling five printing 80 circuits, it is possible to print forty (40) different characters, five by each of the masters, and five by each of the associate step mechanisms. The master A, in addition to the printing magnets 17, 109 and 110 controls printing magnets 124 and 125 controlled 85 respectively by contacts a^2 and a^3 ; and in master B the printing magnets 126 and 127 are controlled respectively by contacts b^2 and b^3 . 90

What I claim is:

1. In a printing telegraph, the combination with a polarized line relay, of a master step by step mechanism controlled by said relay, and an associate step by step mechanism controlled by said master.

2. In a printing telegraph, the combination with a polarized line relay, of a master step by step mechanism controlled thereby, an associate step by step mechanism controlled by said master, and a printing circuit 100 controlled by said associate step by step mechanism.

3. In a printing telegraph, the combination with a polarized line relay, of a master step by step mechanism, an associate step by step mechanism controlled by said master, a printing circuit controlled by said associate step by step mechanism, and a printing circuit controlled directly by said master. 110

4. In a printing telegraph, the combination with a polarized line relay, of two master step by step mechanisms, one controlled by line impulses of one polarity, the other controlled by line impulses of the other polarity, 115 and an associate step by step mechanism controlled by each master, an associate step by step mechanism being actuated upon reception of initial impulses of the kind controlling its master succeeded by impulses of opposite polarity.

5. In a printing telegraph, the combination with a polarized line relay, of a master step by step mechanism controlled thereby, a plurality of associate step by step mechanisms controlled by said master, one or another of said associate mechanisms being selectively controlled by said master according to the number of successive initial impulses of the kind controlling said master. 130

6. In a printing telegraph, the combination with a polarized line relay, of step by step mechanisms controlled thereby, each responsive to characteristic line impulses, 5 and a circuit for actuating each step by step mechanism, the actuating circuit of one step by step mechanism being controlled by the other step by step mechanism.

7. In a printing telegraph, the combination with a polarized line relay, of a master 10 step by step mechanism controlled thereby, an associate step by step mechanism controlled by said master, a printing circuit controlled by said associate step by step mechanism, and means for restoring master and 15 associate mechanisms to normal after printing.

8. In a printing telegraph, the combination with a polarized line relay, of two master 20 step by step mechanisms controlled thereby and responsive respectively to positive and negative line impulses, a plurality of associate step by step mechanisms controlled by each master, an associate step by step mechanism being selected by a master according 25 to the number of initial line impulses to which said master is responsive, a printing circuit controlled by each step by step mechanism, and means for restoring the master and associate step by step mechanisms to 30 normal after printing.

9. In a printing telegraph, the combination with a polarized line relay, of two master step by step mechanisms controlled thereby, an associate step by step mechanism 35 controlled by each master, a printing circuit controlled by each associate step by step mechanism, and means controlled by each master step by step mechanism for interrupting the printing circuit of an unselected associate step by step mechanism.

10. In a printing telegraph, the combination with a line, of a master step by step mechanism controlled by line impulses, an associate step by step mechanism selected 45 by said master step by step mechanism, a printing circuit controlled by said associate step by step mechanism, and means for printing the selected character operative after a period greater than the period between 50 line impulses.

11. In a printing telegraph, the combination with a line, of a master step-by-step mechanism associated therewith and responsive to line impulses, a plurality of associate step-by-step mechanisms controlled 55

by said master, a printing circuit selected by each of said associate step-by-step mechanisms, and means for printing the selected character operative after a period greater than the period between line impulses. 60

12. In a printing telegraph, the combination with a line, of a master step-by-step mechanism associated therewith and responsive to line impulses, an associate step-by-step mechanism controlled by said master, and means controlled by said associate step-by-step mechanism for printing a character operative after a period greater than the period between line impulses. 65

13. In a printing telegraph, the combination with a line, of a master step by step mechanism associated therewith and responsive to line impulses, a plurality of associate step by step mechanisms controlled by said master, and means associated with 70 said master for selecting an associate step by step mechanism depending upon the line impulses received. 75

14. In a printing telegraph, the combination with a line, of a master step by step mechanism associated therewith and responsive to line impulses, a plurality of associate step by step mechanisms controlled by said master, means associated with said master for selecting an associate step by step mechanism depending upon the line impulses received, and a printing circuit controlled by each associate step by step mechanism. 80 85

15. In a printing telegraph, the combination with a line, of a master step by step mechanism associated therewith and responsive to line impulses, a plurality of associate step by step mechanisms controlled by said master, means associated with said master for selecting an associate step by 90 step mechanism depending upon the line impulses received, a printing circuit controlled by each associate step by step mechanism, and means controlled by said master for preventing the operation of the printing 100 circuits of the unselected associate mechanisms. 95

In testimony whereof I have hereunto affixed my signature in the presence of the two subscribing witnesses.
